(57) **CLAIM**

The ornamental design for a display screen with animated graphical user interface for card communication, as shown and described.

DESCRIPTION

FIG. 1 is a first image of a sequence for a display screen with animated graphical user interface for card communication showing the new design;

FIG. 2 is a second image thereof;

FIG. 3 is a third image thereof; and,

FIG. 4 is a fourth image thereof.

The appearance of the animated images sequentially transitions between the images shown in the drawings.

The process or period in which one image transitions to another forms no part of the claimed design.

The outermost broken lines depicting an electronic device form no part of the claimed design. The remaining broken lines illustrate a display screen and portions of the graphical user interface that form no part of the claimed design.
